UNITED STATES PATENT OFFICE

FRITZ STRAUB AND WALTER ANDERAU, OF BASEL, SWITZERLAND, ASSIGNORS TO THE FIRM "SOCIETY OF CHEMICAL INDUSTRY IN BASLE," OF BASEL, SWITZERLAND

METAL COMPOUNDS OF AZO-DYESTUFFS AND PROCESS OF MAKING SAME

No Drawing. Application filed April 25, 1929, Serial No. 358,157, and in France, Japan, and Belgium, March 8, 1929.

The present invention relates to new and valuable metal compounds of azo-dyestuffs deriving from metals of atomic weights ranging from 52 to 58.7. These metal compounds may contain either one metal alone or several metals. In the latter case one or several metals may also not belong to the above mentioned range of atomic weights. The dyestuffs according to the present invention are made by treating the poly-azo-dyestuff of the general formula

in which R is an aryl residue which contains an OH-group in ortho-position to the $\text{N}=\text{N}-$ group, and in which one of the w 's and one of the y 's stand for an OH-group and the other w and the other y for a hydrogen atom, one of the x 's and one of the z 's represent an SO_3H -group and the other x and the other z a hydrogen atom, the sulfo-groups being in meta-position to the OH-groups, further in which the two azo-groups are linked in ortho-position to the OH-groups and in which only one OH-group stands in 8-position, with agents yielding metals of atomic weights ranging from 52 to 58.7 these agents being chosen in such a way that either one or several metals enter the dyestuff molecule whereby in the latter case other metals may also enter the dyestuff molecule. The treatment may be applied in the course of the production of the said poly-azo-dyestuff or to the finished dyestuff, either on the fiber, in the dye-bath or in substance. The dyestuffs of the above formula may be made by coupling a diazo-compound which

contains an OH-group in ortho-position to the $\text{N}=\text{N}-$ group with a mono-azo-dyestuff which is obtained by coupling a diazoized amino-naphthal of the general formula

in which the one w represents one OH-group and the other w a hydrogen atom, the one x an SO_3H -group and the other x a hydrogen atom, and in which the sulfo-group stands in meta-position to the OH-group, in weak acid medium with an amino-naphthal of the general formula

in which the two y 's and the two z 's have the same meaning as above indicated, these two amino-naphthols being chosen in such a manner that the resulting azo-dyestuffs contain only in one 8-position one OH-group.

The metal compounds of the azo-dyestuffs of the above explained general formula deriving from metals of atomic weights ranging from 52 to 58.7 and which may contain still other metals are when dry dark colored powders soluble in water and dilute alkalies to blue to dull reddish-blue solutions and in concentrated sulfuric acid to blue to blackish-green solutions, and dyeing vegetable fiber and especially artificial silk from so-called regenerated cellulose grey, green-grey to blue-grey tints. Particularly useful are those combinations which derive from the mono-azo-dyestuff produced by coupling one

molecular proportion of diazotized 2-amino-5-hydroxynaphthalene-7-sulfonic acid with a second molecular proportion of the same aminonaphthol-sulfonic acid in a feebly acid medium. These dyestuffs, however, do not dye the artificial silks from cellulose esters or cellulose ethers.

The following examples illustrate the invention, the parts being by weight:—

10 10 Example 1.—23.9 parts of diazotized 2-

6-sulfonic acid. The dyestuff thus formed is then isolated.

54 parts of this dyestuff are dissolved in 600 parts of water and mixed with 25 parts of calcined sodium carbonate. At a temperature of 5-7° C. the whole is mixed with the diazo-compound from 16 parts of 5-nitro-2-amino-1-phenol. After a short time coupling is complete. The isolated dyestuff of

20 amino-5-naphthol-7-sulfonic acid are combined in presence of acetic acid with 23.9 parts of 2-amino-5-naphthol-7-sulfonic acid. After the coupling is complete the whole is rendered alkaline with 35 parts of sodium carbonate and coupled with a solution of the diazonium compound from 14.3 parts of 4-chloro-2-amino-1-phenol. After some time the disazo-dyestuff of the formula

is then dissolved in 3000 parts of water and boiled for 24 hours with a solution of chromium fluoride corresponding with 15 parts of Cr_2O_3 . The chromium compound is separated from its solution by means of common salt. It is a dark powder which dissolves in water, dilute alkalies, and concentrated sulfuric acid to a blue solution, dyeing the vegetable fiber as well as artificial silk

40 has been formed and is separated. The product is dissolved in 3000 parts of water, and the whole is heated during 25-30 hours in a reflux apparatus together with a solution of chromium fluoride corresponding with 15 parts of Cr_2O_3 . Then the chromium compound is separated with common salt. When dry it forms a blackish powder which dissolves in water and dilute alkalies to a dull reddish-blue solution, and in concentrated sulfuric acid to a green-black solution. From a bath containing Glauber's salt and neutral or alkaline with sodium carbonate, vegetable fibers and artificial silk are dyed level grey tints.

in a neutral or alkaline Glauber's salt bath level grey-blue tints.

By using 4-chloro-2-aminophenol in the place of 5-nitro-2-aminophenol a chromium compound is obtained which dyes grey tints.

What we claim is:—

1. A manufacture of new metal compounds of azo-dyestuffs by treating a disazo-dyestuff obtained by coupling in an alkaline medium one molecular proportion of a diazo-compound of the benzene series containing a hydroxy-group in ortho-position to the $\text{N}=\text{N}$ -group with a mono-azo-dyestuff of the general formula

120

125

wherein one of the w 's and one of the y 's standing for an OH-group and the other w and the other y for a hydrogen atom, one of the x 's and one of the z 's representing an

55 60 65 70 75 80 85 90 95 100 105 110 115 120 125 130

If in this example the equivalent quantity of 4-chloro-2-amino-1-phenol-6-sulfonic acid is employed as second diazotizing component in place of the 4-chloroaminophenol a dyestuff is obtained which dyes the said fibers blue-grey tints, whereas, when using 4-nitro-2-amino-1-phenol, a dyestuff is formed after chroming that dyes a green-grey of similar properties.

65 70 75 80 85 90 95 100 105 110 115 120 125 130

Example 2.—23.9 parts of diazotized 2-amino-5-naphthol-7-sulfonic acid are combined by known methods in an acetic acid solution with 24 parts of 2-amino-8-naphthol-

SO₃H-group, and the other α and the other β a hydrogen atom, the sulfo-groups being in meta-position to the OH-groups, and only one OH-group standing in 8-position, with agents yielding metals of atomic weights ranging from 52 to 58.7.

2. A manufacture of new metal compounds of azo-dyestuffs by treating a disazo-dyestuff obtained by coupling in an alkaline medium one molecular proportion of a diazo-compound of the benzene series containing a hydroxy-group in ortho-position to the $-\text{N}=\text{N}-$ group with a mono-azo-dyestuff of the general formula

15

25

wherein one of the w 's and one of the y 's standing for an OH-group and the other w and the other y for a hydrogen atom, one of the x 's and one of the z 's representing an SO₃H-group, and the other α and the other β a hydrogen atom, the sulfo-groups being in meta-position to the OH-groups, and only one OH-group standing in 8-position, with agents yielding metals of atomic weights ranging from 52 to 58.7, together with agents yielding other metals capable of forming complex metal compounds with the azo-dyestuffs.

3. A manufacture of new metal compounds by treating a disazo-dyestuff obtained by coupling in an alkaline medium one molecular proportion of a diazo-compound of the benzene series containing a hydroxy-group in ortho-position to the $-\text{N}=\text{N}-$ group with a mono-azo-dyestuff of the general formula

40

with agents yielding metals of atomic weights ranging from 52 to 58.7.

4. A manufacture of new metal compounds of azo-dyestuffs by treating a disazo-dyestuff obtained by coupling in an alkaline medium one molecular proportion of a diazo-compound of the benzene series containing a hydroxy-group in ortho-position to the

$-\text{N}=\text{N}-$ group with a mono-azo-dyestuff of the general formula

with agents yielding chromium.

5. As new products of manufacture the metal compounds deriving from the metals of atomic weights ranging from 52 to 58.7 of disazo-dyestuffs which disazo-dyestuffs are obtained by coupling in an alkaline medium one molecular proportion of a diazo-compound of the benzene series containing a hydroxy group in ortho-position to the $-\text{N}=\text{N}-$ group with a mono-azo-dyestuff of the general formula

wherein one of the w 's and one of the y 's standing for an OH-group and the other w and the other y for a hydrogen atom, one of the x 's and one of the z 's representing an SO₃H-group, and the other α and the other β a hydrogen atom, the sulfo-groups being in meta-position to the OH-groups, and only one OH-group standing in 8-position, which products are when dry dark-colored powders, soluble in water and dilute alkalies to blue to reddish-blue solutions and in concentrated sulfuric acid to greenish-blue to blue solutions, and dyeing vegetable fiber and especially artificial silk from so-called regenerated cellulose fast blue-grey to green-grey and grey tints.

6. As new products of manufacture the metal compounds of disazo-dyestuffs which disazo-dyestuffs are obtained by coupling in an alkaline medium one molecular proportion of a diazo-compound of the benzene series containing a hydroxy group in ortho-position to the $-\text{N}=\text{N}-$ group with a mono-azo-dyestuff of the general formula

- wherein one of the *w*'s and one of the *y*'s standing for an OH-group and the other *w* and the other *y* for a hydrogen atom, one of the *x*'s and one of the *z*'s representing an SO₃H-group, 5 and the other *x* and the other *z* a hydrogen atom, the sulfo-groups being in meta-position to the OH-groups, and only one OH-group standing in 8-position, containing besides metals of atomic weights ranging from 52 to 10 58.7 still other metals capable of forming complex metal compounds with the azo-dye-stuffs, which products are when dry dark colored powders, soluble in water and dilute alkalies to blue to reddish-blue solutions and 15 in concentrated sulfuric acid to greenish-blue to blue solutions, and dyeing vegetable fiber and especially artificial silk from so-called regenerated cellulose fast blue-grey to green-grey and grey tints. 20
7. As new products of manufacture the metal compounds of disazo-dyestuffs which disazo-dyestuffs are obtained by coupling in an alkaline medium one molecular proportion of a diazo-compound of the benzene series containing a hydroxy group in ortho-position to the —N=N— group with a mono-25 azo-dyestuff of the formula

- which products contain metals of atomic weights ranging from 52 to 58.7, forming 40 when dry dark colored powders, soluble in water and dilute alkalies to dull reddish-blue solutions, and in concentrated sulfuric acid to green-black solutions, and dyeing vegetable fiber and especially artificial silk 45 from so-called regenerated cellulose fast grey tints. 50

8. As new products of manufacture the chromium compounds of a disazo-dyestuff, which diazo-dyestuff is obtained by coupling in an alkaline medium one molecular proportion of 1-diazo-2-hydroxy-5-chlorobenzene with the mono-azo-dyestuff of the 55 formula

- which products form when dry a dark colored powder, soluble in water and dilute al-

kalies to dull reddish-blue solutions, in concentrated sulfuric acid to a green-black solution, and dyeing vegetable fiber and especially artificial silk from so-called regenerated cellulose fast grey tints. 70

In witness whereof we have hereunto signed our names this 15th day of April, 1929.
